UNITED STATES PATENT OFFICE.

SIMON COOPER, OF BROOKLYN, NEW YORK, ASSIGNOR TO MENASHA WOODEN WARE CO., OF MENASHA, WISCONSIN, A CORPORATION OF WISCONSIN.

BAILING MACHINE.

Application filed November 21, 1919. Serial No. 339,756.

To all whom it may concern:

Be it known that I, SIMON COOPER, a citizen of the United States, residing at Brooklyn, in the county of Kings and State of New York, have invented certain new and useful Improvements in Bailing Machines, of which the following is a specification.

My present invention relates to machines for applying bails to wooden pails and the like.

The objects of the invention are to provide a simple and practical machine of this character in which the work, so far as possible, will be automatic and will be quickly and accurately performed.

The invention involves a combination of mechanisms including means for supporting and holding the pails, means for driving the bail fastenings into the supported pails and means for locating the bails in proper position to be secured to the pails.

Various other features of the invention will appear as the specification proceeds.

In the accompanying drawings, I have illustrated the invention embodied in a concrete, practical form, but I would have it understood that the invention is susceptible of change and modification without departure from the true spirit and scope of the invention, as defined in the appended claims and I would also have it understood that the terms employed herein are used in a descriptive rather than in a limiting sense, except, as may be required by the prior art.

In the drawings referred to, Figure 1 is a plan view of the machine with the pail supported therein indicated as broken away and appearing in section.

Figure 2 is a view looking at the right hand end of the machine shown in Figure 1, with the pail here also shown in section.

Figure 3 is a side elevation of the machine.

Figure 4 is an enlarged vertical sectional view of the staple guiding and driving mechanism, as taken substantially on the plane of line 4—4 of Figure 5.

Figure 5 is a plan and part sectional view of the parts shown in Figure 4.

Figures 6 and 7 are sectional and broken detail views of the fastening and bail as applied to the pail.

Considering the drawings now in detail, 10 designates the pail mounted on the pail-support. This support is shown in the form

of two arcuate members 11 disposed at the front end of the machine and designed to engage inside and support the pail on a substantially horizontal axis. These supporting members are shown as provided with 60 anvils 12 substantially diametrically opposite and in line with the staple driving means.

The staples are driven by plungers or slides 13 operating in suitable guides at opposite sides of the supported pail and arranged to drive the staples 14 in through the wall of the pail and into engagement with the anvil surfaces at the inside of the pail so as to coil over and rivet the inner 70 ends of the staples as indicated at 15 in Figure 6. These staple driving plungers operate, as indicated in Figure 2, in a common, horizontal plane and are shown as actuated by the rocker arms 16 on the upper 75 ends of rock shafts 17 disposed vertically at opposite sides of the machine and operated from a cam 18 through the medium of a rocker arm 19 which oscillates a double armed lever 20 connected at its opposite 80 ends by links 21, 22 with arms 23 on the lower ends of shafts 17.

The staples are fed to the plungers, in the present disclosure, through vertical guides or channels 24 which terminate at their 85 lower ends in the horizontal passages 25 and the staples are fed to these guides, in the present disclosure, by the detachable guide chutes 26 which are charged with a stack of the staples and then engaged over the permanent guides 24.

In the machine illustrated the pails are centered with respect to the fastening driving means on the pail-support and are temporarily held and secured on said support 95 by clamping devices embodying two pairs of clamp blocks 27, 28 and 29, 30, engaging the pail at substantially diametrically opposite points.

The upper clamps 27 and 29 are carried 100 by the vertically operating slides 31 and 32 respectively and the lower clamps 28 and 30 are carried by the vertically operating slides 33 and 34. The slides of each pair operate in opposition to each other and as 105 shown, advance on lines substantially tangential to the pail to more firmly grip and secure the pail on the support.

The lower clamps 28 and 30 are as indicated in Figure 4 each provided with a 110

space or passage 35 in line with and forming a continuation of the staple passage 25 and the upper clamps are provided with substantially vertical guide passages 36 for 5 directing the eyes 37 of the bails 38 into position to receive the upper prongs of the staples. These guide passages may be continued down into the upper end of the lower clamps, as indicated at 39 in Figure 4.

10 The four clamps are simultaneously operated in the present disclosure from a cam 40 on the cam shaft 41 by means of a lever 42, bearing a roller 43 at its lower end engaging said cam and connected at its upper 15 end by a link 44 with an arm 45 on rock shaft 46 which carries an arm 47 connected with slide 31; the motion of rock shaft 46 being utilized to actuate the other clamps through the medium of rock arm 48, link 20 49 and rock arm 50 on shaft 51 which carries at its forward end a rock arm 52 connected with slide 32, the latter rock shaft 51 being connected with a lower rock shaft 53 through the medium of rocker arms 54, 25 55 and link 56, said last rock shaft 53 bearing an arm 57 connected by link 58 with clamp slide 34 and bearing also an arm 59 connected by link 60 with an arm 61 of rock shaft 62 which carries an arm 63 connected 30 by link 64 with the clamp slide 33.

By the connections described, it will be apparent that all four clamps will be substantially simultaneously operated and will advance in pairs on substantially tangential lines to firmly secure the pail on the support.

The bails, in the machine illustrated are carried by an inclined rack or support made up of the upper and lower parallel bars 65 40 and 66 inclined downward from the rear toward the front of the machine and arranged to receive between them the intermediate handle portions of the bails. The bails feed down this inclined track by gravity 45 into position above the guides for the lower ends thereof.

The different parts of the machine are mounted on a suitable base or frame work and are in the case illustrated all operated 50 from a common drive shaft 67 having a pulley 68 on the rearward end thereof and a fly-wheel 69, said fly-wheel being coupled to the shaft by a one-revolution clutch, of the pin type for instance, whose parts are 55 indicated at 70 and 71, the pin being shown at 72 and controlled by cam 73 on the cam shaft 41. The member 71 of the clutch carries a pinion 74 which meshes with a gear 75 on the cam shaft.

60 When the machine is at rest, the clamps are separated so that a pail can be easily placed over the support. When this is done, the operator actuates the clutch as by means of a control lever 76 causing the motion of 65 the pulley and fly-wheel to be communicated

to the driving pinion 74, which, by reason of the structure of the clutch stops or is thrown out of operation at the end of a complete rotation. In the course of this movement the cam shaft has been turned far 70 enough to cause the cam 40 thereon to advance the clamps into holding engagement with the pail. The operator thereupon withdraws the end bail from the bail support and drops the same downward to bring 75 the eyes on the ends thereof into the guide ways 36 in the upper clamps; when the bail is thus positioned over the pail the attendant again starts the machine as by means of the control lever 76, and the clutch controlling cam this time permits the machine to continue in operation long enough for the cam 18 to actuate the staple driving plungers to drive the staples and then retract and for the cam 40 to then retract the clamps. 80 The machine then stops and with the clamps released the finished pail can be removed and a fresh pail placed in position on the pail-support.

With this machine it will be apparent 90 that the bails can be quickly and securely applied to the pails and further that the machine requires no special skill in its operation.

What I claim is:

1. In a machine of the character described, a pail-support shaped to engage the inside of curved pails, clamping means shaped to engage the outside of said pails, means for advancing said clamping means on lines substantially tangential to the outside curvature of said pails into engagement with the pails on the support and means for securing the ends of bails to the pails. 95

2. In a machine of the character described, 105 a pail-support shaped to engage the inside of curved pails, a pair of clamps shaped to engage the outside of said pails, means for advancing said clamps in opposite directions on lines substantially tangential to the outside curvature of said pails into engagement with the pails on the support and means for securing the ends of bails to the pails.

3. In combination, pail-supporting means for engaging the inside of curved pails, a 115 pair of cooperating clamps operable in reverse directions and on lines substantially tangential to the outside curvature of said pails, one of said clamps having a guide passage for the end of a bail and the companion cooperating clamp having an intersecting passage for bail fastenings and means for driving bail fastenings through the latter passage into the supported pails. 120

4. In a machine of the character described, 125 means for supporting curved pails, clamping means shaped to engage the outside of said pails, means for advancing said clamping means on lines substantially tangential to the outside curvature of said pails into en- 130

gagement with the pails on the support and means for securing the ends of bails to the pails.

5. In a bailing machine, means for supporting curved pails, oppositely working fastening driving plungers operating in a plane substantially diametrical of the pails on said supporting means, pail clamping means shaped to engage the outside of the pails and means for advancing said pail clamping means in a plane substantially at right angles to the plane of operation of the plungers and on lines substantially tangential to the outside curvature of the pails into engagement with the pails on the supporting means.

6. In a machine of the character described, pail-supporting means shaped to engage the inside of curved pails at substantially diametrically opposite points, clamping means shaped to engage the outside of said pails at points over said inner supporting means, means for advancing said clamping means on lines substantially tangential to the outside curvature of said pails into engagement with the pails on the support and means for securing the ends of bails to the pails.

7. In a machine of the character described, a pail-support, clamps for holding the pails on said support, means for positioning bail ends against the sides of the supported pails and means for driving bail fastenings through the bail ends and into the supported pails.

8. In a machine of the character described, a pail-support shaped to engage inside the pails, clamps shaped to engage the outside of the pails, means for advancing said clamps into engagement with the supported pails, said clamps provided with a transverse passage and means for driving bail fastenings through the passage in the clamps and into the clamped pails.

9. In a machine of the character described, a pail-support shaped to engage inside the pails, clamps shaped to engage the outside of the pails, means for advancing said clamps into engagement with the supported pails and means for driving bail fastenings into the clamped pails, said pail clamps having passages for the bail fastenings.

10. In a machine of the character described, a pail-support shaped to engage inside the pails, clamps shaped to engage the outside of the pails, means for advancing said clamps into engagement with the supported pails and means for driving bail fastenings into the clamped pails, said pail clamps having passages for the bail fastenings and further provided with guide passages for locating the ends of the bails in line with the passages for the bail fastenings.

11. In a machine of the character described, pail-support means, means for

clamping the pail on said support provided with guide passages for the ends of the bails and intersecting guide passages for the bail fastenings, and means for driving bail fastenings through said latter passages into the supported pails.

12. In combination, pail-holding means, an inclined bail-support leading toward said pail-holding means, means for guiding the ends of the bails into engagement with the sides of the supported pail and means for fastening the ends of said thus positioned bails to the pails held by said holding means.

13. In combination, a pail-support, guides for supporting stacks of fastenings at opposite sides of pails held by said support, guide passages for bail eyes at the lower ends of said stacks of fastenings and interposed between said stacks and the adjacent sides of pails on the support and plungers operating at the lower ends of the stacks to drive the fastenings at the bottoms of the stacks through the positioned eyes of the bails into the pails on the support.

14. In combination, a pail-support, horizontally operating plungers at opposite sides of said support, substantially vertical guides for directing the ends of bails into engagement with opposite sides of pails on the support and in line with the plungers aforesaid and chutes at the opposite sides of the pail-support for supporting and feeding fastenings into position to be operated on by the plungers aforesaid.

15. In combination, means for supporting pails on a substantially horizontal axis, means for positioning bail ends against the sides of the thus supported pails and substantially horizontally operating plungers at opposite sides of the supported pails for driving fastenings into the pails in engagement with the positioned bail ends.

16. In combination, a pail-support, guides for directing the eyes of bails into approximate engagement with opposite sides of pails on said support, guides for supporting stacks of fastenings in position to be advanced successively into engagement with the thus positioned eyes of the bails and means for successively driving fastenings through the bail eyes into engagement with the supported pails.

17. In combination, means for supporting pails on a substantially horizontal axis, diametrically opposite plungers disposed in a substantially horizontal plane at opposite sides of the supported pails and vertically operating clamps for securing the pails on the support and vertical guides for directing bail ends in proper position over the supported pails.

18. In combination, a pail-support, means for clamping pails on said support, means for positioning bail ends in engagement with the side walls of said supported pails and

- means for driving bail fastenings into the supported pails in line with the thus positioned ends of the bails.
19. In combination, a pail-support, tangentially movable means for clamping the pails on said support, means for driving fastenings into the pails on said support and means for first operating the pail clamps and thereafter the fastening driving means.
- 10 20. In combination, a pail-support, means tangentially movable for clamping the pails on said support, means for driving fastenings into the supported pails and means to operate said parts to first clamp the pails on the support, to then drive the fastenings into the supported pails and to then release the clamps from the pails.
- 20 21. In combination, means for driving fastenings into pails, tangentially movable means for gripping and holding pails in position to be operated on by said driving means and means for operating said parts to hold the pails during operation of the driving means and to thereafter release the pails.
- 25 22. In a bail applying machine, pail gripping and holding means, fastening driving means, operating mechanism for said parts and a control clutch for first stopping said mechanism after operation of the gripping and holding means and then after operation of the driving means.
- 30 23. In combination, a pail-support, clamps for securing pails on said support, plungers for driving fastenings into the supported pails, a shaft provided with cams and connections from said cams for operating said clamps and said plungers.
- 35 24. In combination, a pail-support, clamps for securing pails on said support, plungers for driving fastenings into the supported pails, a shaft provided with cams and connections from said cams for operating said clamps and said plungers, a drive shaft for said cam shaft, a control clutch for said drive shaft and a cam on the cam shaft controlling said control clutch.
- 40 25. A bail applying machine provided at one end with a pail-support and having an inclined bail support extending on a downward incline from the opposite end of the

machine toward said pail support, means for directing the ends of the bails on said latter support into position at opposite sides of the pails on the pail-support and means for driving fastenings into the supported pails and in engagement with the thus positioned bail ends.

55 26. In combination, a pail-support, an inclined bail support leading toward said pail-support, means for guiding the ends of the supported bails into position over the supported pails and means for driving fastenings into the supported pails in engagement with the thus positioned bails.

60 27. In a bailing machine, means for supporting the pails, oppositely working, fastening driving plungers operating in a plane substantially diametrical of the supported pails and pail clamps operating in a plane substantially at right angles to the plane of operation of the plungers and in tangential relation to the surface of the supported pails.

65 70 28. In a pail bailing machine, a pail-support, means for clamping pails on said support, means for positioning bails over the supported pails and clutch controlled mechanism for operating the clamping means and thereafter stopping the machine to enable the location of the bails.

75 80 29. In a pail bailing machine, a pail-support, means for clamping pails on said support, means for positioning bails over the supported pails, clutch controlled mechanism for operating the clamping means and thereafter stopping the machine to enable the location of the bails, bail fastening driving means, said clutch control mechanism including means for operating the machine a second time to drive the fastenings and then release the clamping means.

85 90 95 30. In a pail bailing machine, means for supporting the pails, means for supporting two rows of staples, one row at each side of the supported pail, means for positioning the bail ends in line with the lowermost staple in each row and means for driving said lowermost staples into the opposite sides of the supported pails.

100 In testimony whereof I affix my signature.
SIMON COOPER.
